UNITED STATES PATENT OFFICE.

WILLIAM E. THOMPSON, OF RANGER LAKE, NEW MEXICO.

WASHING-MACHINE.

1,062,130.

Specification of Letters Patent.

Patented May 20, 1913.

Application filed June 3, 1912. Serial No. 701,240.

To all whom it may concern:

Be it known that I, WILLIAM E. THOMPSON, a citizen of the United States, residing at Ranger Lake, in the county of Chaves 5 and State of New Mexico, have invented certain new and useful Improvements in Washing-Machines, of which the following is a specification.

This invention relates to machines for washing clothes, and its object is to provide a machine of this kind whereby the clothes can be thoroughly and quickly cleansed without injury, and also to provide a machine which can be operated manually, or by 15 power.

The invention also has for its object to provide in a machine of the kind stated a novel combination and arrangement of parts to be hereinafter described and claimed.

20 In order that the invention may be better understood, reference is had to the accompanying drawings in which—

Figure 1 is a perspective view of the machine, partly broken away. Fig. 2 is a transverse vertical section thereof. Fig. 3 is a 25 central longitudinal section. Fig. 4 is a horizontal section on the line 4—4 of Fig. 1. Fig. 5 is a vertical sectional detail on the line 5—5 of Fig. 1. Fig. 6 is perspective view showing the pivotal connection of certain parts to be hereinafter described.

Referring specifically to the drawings, 10 denotes a tub or other receptacle in which the clothes to be washed are placed. The 35 bottom 11 of the tub is substantially semi-circular and is made of sheet iron so that the tub may be placed over a fire for the purpose of boiling the water and the clothes. Fig. 1 shows in dotted lines at 10^a a support 40 for the tub, which support may be a furnace.

In the tub is mounted a rubber comprising a slatted basket-like structure which is open at its ends and in two sections. This structure is composed of end bars 12 arranged in pairs at the respective ends of the structure. The lower ends of the bars are curved inward and brought together, and pivoted, as indicated at 13, close to the bottom thereof. The end-bars support slats 14 which extend lengthwise therebetween and are secured thereto in any suitable manner. The slats are set close together and have perforations 15 so that the water may pass therethrough.

55 The rubber herein described is adapted to be alternately collapsed and extended, this

action being permissible as the structure is in two opposite longitudinal sections which are pivoted or hinged at their meeting ends. The following means are provided for effecting this operation of the rubber. A suitable distance above the tub 10 is located a cross-head 16 to the ends of which are fastened depending bars 17 carrying pivoted arms 18 which extend outward and downward in 60 opposite directions, and are pivotally connected, respectively, to the upper outwardly curved ends of the bars 12. Upon elevating the cross-head, the arms swing toward each other and collapse the rubber by drawing 65 the two sections thereof together, and when the cross-head is lowered, the arms are spread and impart a similar movement to the rubber sections. It will therefore be seen that the rubber is alternately collapsed and 70 extended when the cross-head is reciprocated. The cross-head 16 is operated by a lever 19 which is connected to the cross-head by means of a link 20. The lever may be operated by hand; or it can be connected 75 to some suitable source of power.

Inside the rubber is located a vertically reciprocatory plunger 21 which has perforations 22 so that the water may pass therethrough. The plunger is suspended at its 85 ends between bars 23 to which it is made fast in any suitable manner. These bars 23 fit on the bars 17 and are made fast thereto by pins 24 passing therethrough. The bars 23 have a plurality of apertures 25 for the pins, 90 so that the plunger may be vertically adjusted within the rubber according to the quantity of clothes therein. The bars 23 are also connected by a transverse brace 26. Inasmuch as the plunger 21 is connected to 95 the bars 17, it will reciprocate with the cross-head, the plunger traveling upward when the rubber is collapsed, and downward when the rubber is extended. On the inside of the end walls of the tub 10 are vertical 100 guide strips 27 between which the bars 17 work and are guided.

The tub 10 is provided with a suitable lid 28 which is removable in order that the clothes and water may be put in and taken 105 out.

In operation, the clothes to be washed are placed within the rubber below the plunger, and the tub being filled with water, the machine is put in motion. The hereinbefore described movement of the rubber and plunger rubs the clothes and also agitates 110

the same and the water, and the latter is forced through the clothes, thereby quickly and thoroughly cleansing the same without danger of injury. The clothes are put in 5 and taken out by disconnecting the arms 18 from the bars 17 on one side, thus enabling the plunger to be raised without collapsing the rubber.

10 The preferred embodiment of the machine had been shown, but it will be evident that various changes and modifications in the structural details may be made without departing from the spirit and scope of the invention.

15 I claim:

1. A washing machine comprising a receptacle, a rubber in the receptacle, said rubber comprising opposite sections brought together at their lower ends and pivotally 20 connected, means for swinging said sections toward and from one another, a reciprocatory plunger working between the rubber sections, and means for operating the plunger.

2. A washing machine comprising a receptacle, a rubber in the receptacle, said rubber comprising opposite sections brought together at their lower ends and pivotally connected, means for swinging said sections 30 toward and from one another, a reciprocatory plunger working between the rubber sections, said plunger traveling downward when the sections spread, and upward when they swing toward each other, and means 35 for operating the plunger.

3. A washing machine comprising a receptacle, a rubber in the receptacle, said rubber comprising opposite sections brought together at their lower ends and pivotally 40 connected, means for swinging said sections toward and from one another, a vertically adjustable reciprocatory plunger working between the rubber sections, and means for operating the plunger.

4. A washing machine comprising a receptacle, a rubber in the receptacle, said rubber comprising opposite sections brought together at their lower ends and pivotally connected, a reciprocatory cross-head, 45 depending bars carried by the cross-head, pivoted arms carried by the bars and extending

downward and outward therefrom in opposite directions and connected respectively to the rubber sections, and a reciprocatory plunger working between the rubber sections. 55

5. A washing machine comprising a receptacle, a rubber in the receptacle, said rubber comprising opposite sections brought together at their lower ends and pivotally 60 connected, a reciprocatory cross-head, depending bars carried by the cross-head, pivoted arms carried by the bars and extending downward and outward therefrom in opposite directions and connected respectively to 65 the rubber sections, and a plunger carried by the aforesaid depending bars and working between the rubber sections.

6. A washing machine comprising a receptacle, a rubber in the receptacle, said rubber comprising opposite sections brought together at their lower ends and pivotally 70 connected, a reciprocatory cross-head, depending bars carried by the cross-head, pivoted arms carried by the bars and extending 75 downward and outward therefrom in opposite directions and connected respectively to the rubber sections, a plunger working between the rubber sections, and stems carrying said plunger, said stems being fastened 80 to the aforesaid depending bars.

7. A washing machine comprising a receptacle, a rubber in the receptacle, said rubber comprising opposite sections brought together at their lower ends and pivotally 85 connected, a reciprocatory cross-head, depending bars carried by the cross-head, pivoted arms carried by the bars and extending downward and outward therefrom in opposite directions and connected respectively to 90 the rubber sections, a plunger working between the rubber sections, and stems carrying said plunger, said stems being adjustably fastened to the aforesaid depending bars. 95

In testimony whereof I affix my signature in presence of two witnesses.

WILLIAM E. THOMPSON.
